UNITED STATES PATENT OFFICE.

WILLIAM L. KOHLER, OF HAZLETON, PENNSYLVANIA, ASSIGNOR OF TWO-
THIRDS TO EMMA E. KOHLER, OF SAME PLACE.

REFRIGERATOR.

SPECIFICATION forming part of Letters Patent No. 625,569, dated May 23, 1899.

Application filed January 28, 1899. Serial No. 703,751. (No model.)

To all whom it may concern:

Be it known that I, WILLIAM L. KOHLER, a citizen of the United States, residing at Hazleton, in the county of Luzerne and State of Pennsylvania, have invented certain new and useful Improvements in Refrigerators, of which the following is a specification.

The object of my invention is to provide, in connection with a refrigerator arranged to promote a continuous circulation of the internal air, which circulation is actuated by the difference in temperature between the ice-chamber and the provision-chamber, an odor-absorbing material in contact with the internal circulating air and means for ventilating said absorbent material continually and without permitting said ventilation to interfere with the normal air circulation within the refrigerator. This object I accomplish in the manner described in the following specification and illustrated in the accompanying drawings, in which—

Figure 1 is a perspective view of a refrigerator embodying my improvements, the top and lower front portion being broken away to show the internal construction. Fig. 2 is a plan view of the upper casing or cover with the top boards removed, and Fig. 3 is a vertical section through the refrigerator on the line 3 3 of Fig. 2.

Referring to the drawings, 1 indicates the refrigerator-chest, the side and bottom walls of which are made double and lined with paper, the space between said walls being mainly filled with powdered charcoal or other non-heat-conducting material. For the purpose of promoting air circulation, as herein-after explained, I prefer to omit the non-conducting material from a part 2 of the walls, as shown in Fig. 3.

The refrigerator is provided with an ice-chamber 3 in its upper portion, which chamber, as shown in the drawings, is separated from the provision-chamber 4 by a vertical partition 5 and a horizontal partition 6. The provision-chamber 4 occupies the remainder of the space within the refrigerator-walls extending below the ice-chamber and upward alongside of the vertical partition 5. A suitable vent or opening 7 is provided between the lower part of the ice-chamber and the

lower portion of the provision-chamber, so as to permit the cold air from the ice-chamber to fall into the provision-chamber. The chambers are provided with suitable doors 8, 55 the ice-chamber being also provided with a drip-pipe 9 and the provision-chamber with any desired arrangement of trays or shelves 10. The arrangement of the chamber is such that the cold air will fall from the ice-chamber into the provision-chamber and becoming warmer therein will pass upward through the provision-chamber and over the vertical partition 5, a suitable duct being arranged to convey the circulating air back into the ice-chamber. I have shown the preferred arrangement of chambers for producing an internal air circulation; but it will be understood that other arrangements of chambers which will promote a continuous circulation 70 of the air may be employed in connection with my improved means for purifying the air and relieving it from odors, which will now be described.

The top or cover for the ice and provision chambers consists of a hollow casing 11, extending over both chambers and containing a body of odor-absorbing material 12. The lower wall 13 of the casing is provided with an opening 14 over the provision-chamber and 80 a similar opening 15 over the ice-chamber, and these openings are connected by a perforated duct 16 within the casing. Within this duct is arranged a quantity of absorbent material 17, which is held in place by wire-netting or other suitable perforated material 18. The normal circulation of the air is from the ice-chamber to the provision-chamber, thence throughout outlet-opening 14, duct 16, and inlet-opening 15 back to the ice-chamber. 90

In order to expose the air which circulates within the refrigerator to the large body of absorbent material 12, a duct 19, having perforated walls 20, is arranged within the casing, said perforated duct extending from the 95 outlet-opening 14 to the exterior of the casing. As shown in the drawings, this duct extends straight back to the rear of the casing; but it will be understood that it may take any direction from the opening 14 to the exterior, 100 and it may be provided with branches extending into the body of absorbent material, if

desired, and with several exterior openings. The duct is shown in the drawings in its simplest form, and this arrangement is suitable for refrigerators of ordinary size.

5 At some point in the perforated duct I arrange a porous barrier or partition 21. As shown in the drawings, this partition consists of a quantity of the absorbent material retained between perforated or gauze plates 22, 10 which extend across the duct near its outer end. The object of this partition is to check sudden drafts through the duct which might be induced by the opening and closing of the refrigerator-doors, and yet at the same time 15 provide for a gentle aeration of the body of absorbent material through said partition. The odor-absorbing material which I prefer to use is finely-divided charcoal. By arranging the partition a short distance from the 20 outer end, as shown, the charcoal is exposed to the external air through the walls of the ducts 20 between said partition and the end of the duct.

From the foregoing description it will be 25 readily understood that when the refrigerator-doors are closed the internal air will circulate in the direction indicated by the arrows and in its passage before reentering the ice-chamber will be more or less exposed to 30 the whole body of charcoal, as well as to the charcoal in the duct 16, so that the odors are continually absorbed. At the same time the body of charcoal is always more or less exposed to the atmosphere through the porous partition 21 and the walls 20 in the rear of said partition. The slight drafts of air through said partition caused by the occasional opening and closing of the refrigerator-doors also aids in the aeration of the absorbent 40 body, although these drafts are checked to such an extent by said partition that very little of the air is drawn through the opening 14.

In order to promote the circulation of the 45 internal air, I prefer to omit the non-heat-conducting material from a part of the upright wall of the provision-chamber, as indicated by the reference-numeral 2 in Fig. 3 of the drawings. The inlet-opening 15 to the 50 ice-chamber I also restrict in size, so that the air-current entering through said opening will be more forcibly thrown down upon the ice than if a large opening were employed, and a better circulation of the air around the ice is thus produced.

55 Having described my invention, what I claim, and desire to secure by Letters Patent of the United States, is—

1. In a refrigerator, the combination with 60 an ice and a provision chamber arranged to promote a continuous circulation of the internal air through said chambers, of a casing containing a body of absorbent material, said material being exposed to the external at-

mosphere, an outlet-opening between said provision-chamber and the casing, an inlet-opening between said casing and the ice-chamber, and a perforated duct within the casing leading through said absorbent material and connecting said openings, whereby the entire 70 body of internal air is caused to circulate through said duct, substantially as described.

2. In a refrigerator, the combination with an ice and a provision chamber arranged to promote a continuous circulation of the internal air, of a casing containing a body of absorbent material and forming a cover for said chambers, an outlet-opening between said provision-chamber and the casing, an inlet-opening between said casing and the ice-chamber, a duct connecting said openings, a 75 perforated duct extending through the body of absorbent material and connecting the said outlet-opening with the external atmosphere, and a porous partition in said perforated duct, 80 substantially as described.

3. In a refrigerator, the combination with an ice and a provision chamber, separated by a vertical partition, the lower part of said ice-chamber communicating with the provision-chamber, of a casing containing a body of absorbent material and forming a cover for said chambers, an outlet-opening between said provision-chamber and the casing, an inlet-opening between said casing and the ice-chamber, a duct connecting said openings and 90 having an absorbent material therein, a perforated duct extending through the body of absorbent material and connecting said outlet-opening with the external atmosphere, 95 and a partition of absorbent material in said 100 perforated duct, substantially as described.

4. In a refrigerator, the combination with an ice and a provision chamber, separated by a vertical partition, the lower part of said ice-chamber having an opening communicating with the provision-chamber, of a casing containing a body of absorbent material exposed to the external atmosphere, said casing forming a cover for said chambers, an outlet-opening between said provision-chamber and the casing, said opening being in communication with the body of absorbent material, an inlet-opening between said casing and the ice-chamber, a perforated duct within the casing leading through said absorbent material and connecting said outlet and inlet openings, whereby the entire body of internal air is caused to circulate through said duct, and an absorbent material in said duct, substantially as described.

In testimony whereof I affix my signature in presence of two witnesses.

WILLIAM L. X KOHLER.
